MOULDING STRIP

Virgil M. Exner, Birmingham, and Clifford C. Voss, Clawson, Mich., assignors to Chrysler Corporation, Highland Park, Mich., a corporation of Delaware

Application May 11, 1955, Serial No. 35,934

Term of patent 14 years

(Cl. D14—6)

Fig. 1.

Fig. 1 is a side elevational view of a moulding strip showing our new design;

Fig. 2 is an enlarged fragmentary view of the circled areas designated by the numeral 2 in Fig. 1;

Figs. 3 and 4 are enlarged sectional views taken on the lines 3—3 and 4—4 of Fig. 2; and

Figs. 5 and 6 are enlarged sectional views taken on the lines 5—5 and 6—6 of Fig. 1.

The automobile shown by means of dotted lines is only disclosed for illustrative purposes.

We claim:

The ornamental design for a moulding strip, substantially as shown and described.
